UNITED STATES PATENT OFFICE.

HARRY S. ANDERSON, OF NEW YORK, N. Y.

DESIGN FOR A POWDER BOX OR SIMILAR ARTICLE.

Application filed October 18, 1924. Serial No. 11,108. Term of patent 7 years.

To all whom it may concern:

Be it known that I, HARRY S. ANDERSON, a citizen of the United States, and a resident of the county of Bronx, city and State of New York, have invented a new, original, and ornamental Design for Powder Boxes or Similar Articles, of which the following is a specification, reference being had to the accompanying drawing, forming a part hereof.

The drawing shows a perspective view of the powder box or similar article.

I claim:

The ornamental design for a powder box or similar article, substantially as shown.

HARRY S. ANDERSON.
